CLAIM

I claim the ornamental design for a satellite dish mount,
substantially as shown and described.

DESCRIPTION

FIG. 1 is a perspective illustration of the inventive mount;
FIG. 2 is a top view of the inventive mount;
FIG. 3 is a front view of the inventive mount;
FIG. 4 is a side view of the inventive mount, the other side
view being wholly symmetrical;
FIG. 5 is a bottom view of the inventive mount; and,
FIG. 6 is a rear view of the inventive mount.
